SANITARY TEMPORARY PANTY

Jacob Brody and Harry Brody, Brooklyn, N. Y.

Application June 8, 1940, Serial No. 339,538

2 Claims. (Cl. 2—224)

This invention relates to new and useful improvements in sanitary temporary panties.

The invention proposes the construction of sanitary temporary panties preferably made from sanitary paper and adapted to be worn by women when trying on bathing suits, underwear or other similar garments.

More specifically, the invention proposes to characterize the panty by a strip of sanitary sheet material having a central reduced section for engaging the crotch of a wearer, and end sections for extending up the front and back of the wearer to the waist, and means for securing said panties in position.

Still further the invention proposes that said sanitary sheet material comprise water proofed paper.

Another object of the invention resides in the provision of simple and efficient means for securing the panties in position. Particularly, it is proposed that a waist strap be provided for this purpose. It is proposed that the waist strap be formed of several separate sections of material capable of being tied or connected together.

In another form of the invention means is proposed movably mounted on adjacent strap sections for releasably holding adjacent points together to facilitate engagement of the panty on a person.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a person wearing a pair of temporary sanitary panties constructed in accordance with this invention.

Fig. 2 is a developed view of the panties, per se.

Fig. 3 is a fragmentary enlarged sectional view taken on the line 3—3 of Fig. 2.

Fig. 4 is a fragmentary view similar to a portion of Fig. 2 but showing a modified construction.

Fig. 5 is a sectional view taken on the line 5—5 of Fig. 4.

Fig. 6 is a perspective view of a pair of sanitary panties constructed in accordance with another form of this invention.

Fig. 7 is a transverse sectional view taken on the line 7—7 of Fig. 6.

Fig. 8 is a front elevational view of a pair of

sanitary temporary panties constructed according to another form of this invention.

Fig. 9 is a plan view of Fig. 8.

Fig. 10 is a fragmentary perspective view showing a still further modified form of the invention.

The sanitary temporary panties, in accordance with this invention, includes a strip of sanitary sheet material 10, preferably of water proof paper, and having a central reduced section 10^a for engaging the crotch of a wearer, and end sections 10^b for extending up the front and back of the wearer to the waist. Means is provided for securing the panties in position. This means 15 comprises a strap 11 mounted on each end section 10^b for engaging about the waist.

Each strap 11 comprises a strip of material which is bent along its longitudinal center 11^a so that there are side portions or layers, and these side portions are extended along the edge portions of the end section 10^b. A longitudinal line of stitches 12 is engaged through the layers of the strap 11 and the end section 10^b for securing the strap in position.

It is proposed that these temporary panties be sold to stores selling bathing suits, underwear, and the like. When women desire to try on such garments the sales person supplies the customer with one of the sanitary panties. After it is 20 donned the customer tries on the garment. Thereafter the sanitary panties are destroyed.

The straps 11 permit the panties to be engaged on women of different sizes. It is necessary that adjacent ends of the straps 11 be first tied together at approximately correct positions to fit 25 a particular waist size. Then the panties are engaged on the person and the other ends of the straps 11 are tied together. This is illustrated in Fig. 1.

In Figs. 4 and 5 a modified form of the invention has been disclosed which distinguishes from the prior form merely in the manner in which the strap 11 is secured upon the end section 10^b of the sanitary sheet material 10. The strap 11 30 is bent along its longitudinal center 11^a so that the side portions or layers engage over the edges of the end 10^b. Then the layers are secured to the end section 10^b by adhesive material 12. In other respects this form of the invention is similar to the previous form.

In Figs. 6 and 7 still another form of the invention is disclosed which distinguishes from the prior form in the provision of means movably mounted on adjacent strap sections 11 for releasably holding adjacent points together to 35

adapt the waist strap to waists of different sizes. More particularly, this means includes a ring member 14 through which the adjacent ends of the strap sections 11 are engaged. The ring member 14 has inwardly stamped prongs 14^a which bear against the strap sections 11 for frictionally holding the same. One side 14^b of the ring member 14 is slit open and the material to the sides of the slit are flared outwards, indicated by reference numerals 14^c, to facilitate engaging the strap sections 11 through the ring member 14. It is merely necessary that the strap sections be forced upwards in between the outwardly flared ends 14^c.

When donning this temporary panty the wearer steps across the sheet material 10 so that the central section 10^a engages the crotch; then holds the free ends of the straps 11 with one hand, and with the other hand slips the ring 14 along the length of the ends of the straps 11 until the ring 14 reaches an approximate correct position. Then the free ends of the straps 11 are tied together, and thus the panties are secured in position on the wearer.

In Figs. 8 and 9 another form of the invention has been disclosed which distinguishes from the prior forms in the fact that the panties are provided with an elastic band 15 mounted along the top edges of the end sections 10^b. This elastic band is formed from a strip of elastic material which has its ends 15^a stitched together. The panties are engaged on a person by stepping through the band 15 so that the crotch section 11^a is in proper position at the crotch.

In Fig. 10, an elastic strip 16 is shown to be inserted in a pocket 17 formed by the folded edge portion 18 of the sanitary sheet material 10'. The edge portion 18 is secured to the sheet material 10' by adhesive 19, or by any other means.

While we have illustrated and described the preferred embodiments of our invention, it is to

be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. In a sanitary temporary panty of water-proofed paper having separate strap sections adapted to be engaged about one's waist and tied at the sides of one's body for supporting said panties, means temporarily connecting together adjacent strap sections to one side of one's body while the strap sections on the other side of one's body are being tied to assist in positioning the panties on one's body, comprising a ring engageable upon the strap sections to one side of one's body, and means on said ring frictionally maintaining said ring in various shifted positions along the length of said strap sections, comprising resilient prongs stamped from opposite sides of said ring and engaging opposite sides of said strap sections.
2. In a sanitary temporary panty water-proofed paper having separate strap sections adapted to be engaged about one's waist and tied at the sides of one's body for supporting said panties, means temporarily connecting together adjacent strap sections to one side of one's body while the strap sections on the other side of one's body are being tied to assist in positioning the panties on one's body, comprising a ring engageable upon the strap sections to one side of one's body, and means on said ring frictionally maintaining said ring in various shifted positions along the length of said strap sections, said ring having an open side with outwardly flared end portions through which said strap sections may be threaded.
